Primary Examiner — Caron D Veynar*Assistant Examiner* — Katrina N Gonzalez(57) **CLAIM**

The ornamental design for a treadmill, as shown and described.

DESCRIPTION

FIG. 1 is a perspective view of a treadmill of the present invention;

FIG. 2 is a first end view of the treadmill of FIG. 1;

FIG. 3 is a second end view of the treadmill of FIG. 1;

FIG. 4 is a right side view of the treadmill of FIG. 1;

FIG. 5 is a left side view of the treadmill of FIG. 1;

FIG. 6 is a top view of the treadmill of FIG. 1; and,

FIG. 7 is a bottom view of the treadmill of FIG. 1.

The broken lines are shown for the purpose of illustrating parts of the treadmill that form no part of the claimed design.

1 Claim, 6 Drawing Sheets(56)
